ATTORNEY

UNITED STATES PATENT OFFICE

CHARLES E. JONES, OF GRIFFIN, GEORGIA

CONSTRUCTION UNIT

Application filed April 18, 1929, Serial No. 356,170.

This invention appertains to improvements in construction units generally, and more particularly to a building block or brick type of such units to be employed in erecting walls of buildings and the like.

In the building practice, one of the major difficulties arising therein has been the necessity of making attachments of various kinds and descriptions directly to the concrete or brick walls of buildings, as in the case of attaching wood or metal furring strips and lathing thereto for plastering and other similar purposes, or in the securing to the same of cables, conduits, pipes and the like, and which has heretofore been accomplished only at great inconvenience, labor and expense by the drilling of holes in the walls or the insertion of metal clips and the like in the mortar joints between block or brick units forming the wall.

Therefore, it is an object of the present invention to provide a construction unit, wherein a means is provided which will overcome the difficulty aforesaid in a highly efficient manner and make it comparatively easy to secure nails, pins and other types of fastenings in the same without, in any way, resorting to the drilling or chiselling of holes therein for the purpose, and at the same time, eliminating any necessity for the employment of extraneous means for completing the securing of the fastenings in place.

Another object of the invention is to provide construction units as herein characterized, which will readily admit of the driving or screwing of nails, pins or screws and the like into units made from hard and ordinarily impenetrable materials such as brick, concrete blocks and the like, with a facility heretofore obtaining only in the securing of fastenings of this character in materials of a softer nature.

With the foregoing and other equally important objects and advantages in view, the invention resides in the certain new and useful construction and arrangement as will be hereinafter more fully described, set forth in the appended claims and illustrated in the accompanying drawings, in which:

Figure 1 is a perspective view of a concrete block or brick wall construction, showing a practical embodiment and application of the invention;

Figure 2 is a vertical transverse section through the wall and a furring strip or the like secured thereto in accordance with the invention;

Figure 3 is a perspective view of a slightly modified form of the block or brick per se;

Figure 4 is a similar view of another slightly modified form of the block or brick; and

Figure 5 is another similar view of a further modified form thereof.

Referring to the drawings, wherein like characters of reference designate corresponding parts throughout the several views thereof, and more particular to Figures 1 and 2, the embodiment of the invention, as shown therein by way of example, is constituted in a building unit 10, of a hard and ordinarily impenetrable material, such as concrete, baked clay and the like, which when shaped or molded, has one or more slots 11 formed therein and opening through at least one of the opposite side faces of the same, and extending either horizontally or transversely thereof, or both, as may be desired. Each slot 11 in a building unit 10 is made with its opposite side walls converging toward one another inwardly of the unit bodies, so that the same is substantially triangular in cross section and comparatively narrow with respect to its depth of penetration. Also, the slots 11 will be preferably formed in the plane of the horizontal and/or transverse centers of the unit 10 so as to not unduly weaken the block or brick structure.

In use, the units 10 will be laid in the usual manner to form a wall or other structure, with the slots 11 therein faced inwardly of the completed wall, in the case of the attaching thereto of furring strips or the like *a*, as shown in Figures 1 and 2, for plastering and other wall finishing operations, or outwardly, as in the case of the attaching of the strips *a* for pebble-dashing or other exterior finishes. The arrangement of the slots 11, in building units of the nature mentioned, also

provides an excellent means for the installation of chimney and wall flashing as will be obvious.

In effecting an attachment of building elements, such as the furring strips *a* in position on a wall, fastening elements such as the nails *b*, will be driven through the strips *a* in the usual manner and the points of the nails *b* allowed to enter the slots 11. Now, as the 10 nails *b* are driven to completely secured position, the pointed ends thereof will penetrate the gradually constricted inner side walls of the slots 11 and will be firmly held therein against displacement by the frictional 15 effect between the same and the opposed walls of the slots, substantially as is shown in Figure 2.

In the case of the flashing of chimneys and walls, one edge of the flashing materials can 20 be readily forced into the aligned slots 11 of adjacent building units and tightly wedged therein, with or without further securing.

In Figure 3, the block or brick 10^a therein illustrates the arrangement of the slot 11^a 25 when formed co-extensive with one piece of the same transversely thereof, as distinguished from the slot 11 formed coextensively with the face in the longitudinal direction, as shown in Figures 1 and 2.

30 As shown in Figure 4, instead of one slot being formed either longitudinally or transversely, or both, of one face of a block or brick, a series of relatively short slots 11^b may be substituted therefor, and these will preferably be disposed in equidistantly spaced relation one with respect to the other, but unequally so, if occasion demands.

In Figure 5, the block or brick 10^c illustrates an arrangement of a series of alternately disposed short slots 11^c and circular 40 openings or punctures 12, which are preferably laid in aligned relation along the longitudinal center of one face thereof, substantially as shown.

45 In each instance of these modified forms of the invention, the slots 11^a, 11^b and 11^c, and the circular openings or punctures 12, are tapered inwardly of the block or brick face, so that the same securement of the fastenings to be engaged therein will obtain.

50 Without further description, it is thought that the features and advantages of the invention will be readily apparent to those skilled in the art, and it will of course be understood that changes in the form, proportion and minor details of construction may be resorted to, without departing from the spirit of the invention or its scope as claimed.

I claim:

60 1. A construction unit formed of an ordinarily impenetrable material and having a wedged shaped opening therein for the frictional engagement therein of fastenings of other building units to be attached thereto.

65 2. A construction unit formed of an ordi-

narily impenetrable material and having a wedge shaped slotted opening therein for the frictional engagement therein of fastenings of other building units to be attached thereto.

3. A construction unit formed of an ordinarily impenetrable material and having a wedge shaped slotted opening therein for the frictional engagement therein at any point along its length of driven fastenings of other building units to be attached thereto. 70

4. A construction unit formed of an ordinarily impenetrable molded material and having a wedge shaped opening formed in a face thereof when molded, said opening being adapted for the frictional engagement therein of fastenings of other building units 80 to be attached thereto. 75

5. A construction unit formed of an ordinarily impenetrable molded material and having a wedge shaped slotted opening formed in the face thereof when molded, said opening being adapted for the frictional engagement therein at any point along its length of fastenings of other building units 85 to be attached thereto. 90

6. A construction unit formed of an ordinarily impenetrable molded material and having a wedge shaped slotted opening formed in a face thereof when molded, said opening being adapted for the frictional engagement therein at any point along its length of driven fastenings of other building units to be attached thereto. 95

7. A construction unit formed of an ordinarily impenetrable molded material and having an elongated wedge shaped slot formed crosswise of the face thereof when molded, said slotted opening being adapted for the frictional engagement therein at any point along its length of driven fastenings and the like of other building units to be attached thereto. 100 105

8. A construction unit formed of an ordinarily impenetrable molded material and having an elongated wedge shaped slot formed centrally in a face thereof when molded, said slot being adapted for the frictional engagement therein at any point along its length of driven fastenings and the like of other building units to be attached thereto. 110 115

9. A construction unit formed of an ordinarily impenetrable molded material and having an elongated wedge shaped slot formed lengthwise in a face thereof when molded, said slotted opening being adapted for the frictional engagement therein at any point along its length of driven fastenings and the like of other building units to be attached thereto. 120
